(57) **CLAIM**

The ornamental design for a stock for a gun, as shown and described.

DESCRIPTION

FIG. 1 is a perspective view of a stock for a gun in accordance with my new design, the stock for a gun including a variably adjustable cheek piece and butt plate adjustment, the variably adjustable cheek piece and butt plate adjustment being in a collapsed configuration;

FIG. 2 is a front, left, top perspective view of the stock for a gun of FIG. 1;

FIG. 3 is a front view of the stock for a gun of FIG. 1;

FIG. 4 is a rear view of the stock for a gun of FIG. 1;

FIG. 5 is a left side view of the stock for a gun of FIG. 1;

FIG. 6 is a right side view of the stock for a gun of FIG. 1;

FIG. 7 is a top view of the stock for a gun of FIG. 1;

FIG. 8 is a bottom view of the stock for a gun of FIG. 1;

FIG. 9 is a rear, left, bottom perspective view of the stock for a gun of FIG. 1;

FIG. 10 is a perspective view of the stock for a gun of FIG. 1, the variably adjustable cheek piece and butt plate adjustment being in an extended configuration;

FIG. 11 is a front, left, top perspective view of the stock for a gun of FIG. 10;

FIG. 12 is a front view of the stock for a gun of FIG. 10;

FIG. 13 is a rear view of the stock for a gun of FIG. 10;

FIG. 14 is a left side view of the stock for a gun of FIG. 10;

FIG. 15 is a right side view of the stock for a gun of FIG. 10;

FIG. 16 is a top view of the stock for a gun of FIG. 10;

FIG. 17 is a bottom view of the stock for a gun of FIG. 10; and,

FIG. 18 is a rear, left, bottom perspective view of the stock for a gun of FIG. 10.

The broken lines immediately adjacent the shaded areas represent the bounds of the claimed design. All broken lines are directed to environment and are for illustrative purposes only and form no part of the claimed design.

1 Claim, 14 Drawing Sheets
